(57) **CLAIM**

The ornamental design for a brassiere having a clear back strap, as shown and described.

DESCRIPTION

FIG. 1 is a perspective view of the present invention shown with a continuous one piece underwire depicted on a model (the model shape depicted in broken lines forms no part of the claimed design);

FIG. 2 is a front view of the present invention;

FIG. 3 is a top view of the present invention;

FIG. 4 is a bottom view of the present invention;

FIG. 5 is a back view of the present invention;

FIG. 6 is a left end view of the present invention, and;

FIG. 7 is a right cross section view of the present invention;

FIG. 8 is a perspective view of an alternative embodiment of the present invention shown with two separate underwires, one under each cup, depicted on a model (the model shape depicted in broken lines forms no part of the claimed design);

FIG. 9 is a front view of the present invention;

FIG. 10 is a back view of the present invention;

FIG. 11 is a left end view of the present invention; and,

FIG. 12 is a right cross section view of the present invention.

The broken lines shown on the surface of the claimed design throughout the views are understood to represent stitching.
